FIG. 1

FIG. 2

FIG. 3

FIG. 4

INVENTOR

ALBERT R. DERGE

BY
Harry C. Schroeder
ATTORNEY

UNITED STATES PATENT OFFICE.

ALBERT R. DERGE, OF BERKELEY, CALIFORNIA.

FLATIRON HOLDER.

Application filed December 27, 1923. Serial No. 632,940.

My invention is an improved flatiron holder, the object of which is to so insulate the holder that the danger of fire, due to igniting the ironing board, is entirely eliminated.

Another object is to provide a holder having an inner tray and an outer tray which are separated and insulated from each other by a layer of insulating material.

10 A further object is to provide a holder which is simple in construction and inexpensive to manufacture.

Other objects and advantages will be further described in the following detailed description.

In the annexed drawing in which my invention is illustrated:

Figure 1 is a plan view of my holder.

Figure 2 is a sectional view taken on the line 2—2 of Figure 1.

Figure 3 is a plan view of the sheet forming the outer tray, prior to bending in shape.

Figure 4 is a fragmentary sectional view taken on line 4—4 of Figure 1.

25 Referring more particularly to the drawing, my holder comprises an outer tray 1, the side walls 2 of which converge upwardly. The inner tray 3 in which the iron is adapted to rest has converging side walls 4. These 30 walls extend upwardly slightly above the upper edge of the walls 2. Thus, if the iron is permitted to rest on the walls 4, it will not touch the tray 1 and consequently will not heat said tray.

An insulating and fire resistant packing 35 5 (such as asbestos) is placed between the trays 1 and 3 and if desired may also be formed in the shape of a tray, with converging side walls.

The trays 1 and 3 are preferably stamped 40 from a single piece of metal, and the tray 1 as shown at 6 has one end left unfolded. With this end open the packing 5 and tray 3 is inserted, after which the end is folded upwardly and the flanges 7 thereon are riveted to the adjacent side.

The converging sides of the trays 1 and 3 enables the tray 3 to be held in place without a connecting pin or link between the two trays. The packing 5 serves to hold the tray 50 3 in position and insulates it from the outer tray 1, thus eliminating all possibility of heating the outer tray, and thus causing a fire.

Having described my invention, I claim: 55

A flatiron holder comprising an outer tray having upwardly and inwardly converging side walls, an inner tray of similar shape positioned within said outer tray in spaced relation thereto, the walls of said inner tray 60 projecting above the plane of the upper edges of the walls of the outer tray, and insulating material filling the space between said trays.

In testimony whereof I affix my signature.

ALBERT R. DERGE.
